DISPLAY DEVICE

Rica E. Kaplan, New York, N. Y.

Application February 19, 1951, Serial No. 14,274

Term of patent 14 years

(Cl. D80—1)

To all whom it may concern:

Be it known that I, Rica E. Kaplan, a citizen of the United States and a resident of New York city, in the county of New York and State of New York, have invented a new, original, and ornamental Design for Display Device, of which the following is a specification, reference being had to the accompanying drawings, forming a part hereof.

Fig. 1 is a front elevational view of a display device showing my new design; and

Fig. 2 is an end elevational view thereof.

The back of the device is substantially plain.

I claim:

The ornamental design for a display device, as shown and described.

RICA E. KAPLAN.
